TENSIONING MECHANISM FOR WINDING APPARATUS

Leonard C. Sheldon, Hillsdale, N. J.

Application July 30, 1932, Serial No. 626,596

8 Claims. (Cl. 242—45)

My present invention relates to the winding of elastic threads, and has particular reference to the winding of elastic threads in the manufacture of golf balls and the like.

5 In the manufacture of golf balls the ball core is positioned between rollers, one of the rollers being positively driven, and another of the rollers being resiliently pressed against the core, whereby the rotation of the positively driven roller causes the 10 ball core to roll and pull elastic thread from a source of supply, thus winding the elastic thread upon itself to build up the ball.

It has been found difficult to control the tension of the elastic thread during winding, as the speed 15 of rotation of the ball surface changes as the ball builds up, and the speed of feed of the elastic thread changes in a corresponding manner. It is the principal object of my invention to provide a tensioning apparatus for the elastic thread that 20 will maintain a constant tension on the thread regardless of its speed of feed. It has been found desirable to form golf balls with a core of threads wound under one tension, and an outer layer of threads wound under a different tension; this 25 procedure has heretofore required different winding machines, and resultant loss of time in changing over. It is therefore a further object of my invention to provide a tensioning apparatus which 30 may be regulated to change the tension on the thread, the change being gradual or abrupt, as desired, regardless of the speed of feed of the thread.

With the above and other objects and advantageous features in view, the invention consists 35 of a novel method of winding, and a novel apparatus for winding, more fully disclosed in the detailed description following, in conjunction with the accompanying drawings, and more specifically defined in the claims appended hereto.

40 In the drawings,

Fig. 1 is an elevation, partly broken away, of a 45 golf ball winding apparatus;

Fig. 2 is a side elevation of the lower portion thereof;

Fig. 3 is an enlarged plan view, partly in section, of the tensioning mechanism;

Fig. 4 is a diagrammatic view showing the 50 thread travel through the tensioning device;

Fig. 5 is an elevation, partly in section, of a 55 clutch mechanism for a modified construction of tensioning device;

Fig. 6 is an elevation, and Fig. 7 is a section thereof on the line 7—7 of Fig. 6, of a further modified form of tensioning device; and

55 Figs. 8 and 9 are respectively a plan and an

elevation of a still further modified form of tensioning device.

Referring to the drawings, the ball winding machine 10 includes a base 11, on which a support standard 12 is mounted to rotatably support a reel 13 of elastic thread or the like, the reel being provided with a central bore or the like to receive a fixed conical bearing 14 and a movable conical bearing 15, in the usual manner. The thread, indicated at 16, is carried through a tensioning mechanism, hereinafter described, and is wound on a ball core 17, which is rotatably seated on two spaced rollers 18, 19, having arcuate ball receiving recesses, one of said rollers being positively driven; a third roller 20 of similar formation is rotatably mounted in a support arm 21 which is pivoted to the machine base and is resiliently urged downward by a spring or the like 22 to bring the roller 20 into contacting engagement with the rotating ball core. 75

The tensioning mechanism includes spaced grooved pulleys 23, 24 which are rotatably mounted on shafts 25, 26, ball bearings being utilized to reduce friction, the pulleys having hubs 27, 28 to which gears 29, 30 are secured, these 80 gears being of different diameter, and in mesh. As will be noted in Fig. 4, the thread 16 is wound around pulley 24, is led to pulley 23 to wind around in the reverse direction, and is then conveyed to the ball core 17. 85

It is therefore clear that the rotating ball core pulls the thread as it rolls, thus winding the thread about itself to build up the ball, the thread being drawn through the two pulleys and from the supply reel. Since the thread encircles the 90 pulleys, it cannot slip; the pulleys have a different rotative speed because of their positive gearing, and the thread is therefore fed to the ball core under a constant tension, the amount of the tension depending on the proportionate 95 speeds of the gears. Thus, if the peripheries of gears 29 and 28 are in the proportion of 5 to 1, the thread will be stretched 1 in 5, and this tension will be maintained regardless of the changing pull of the ball core as its diameter 100 increases and its speed of rotation changes.

It has been found desirable, in certain constructions, to change the tension so as to obtain a very hard center and a more resilient surface covering. This construction has heretofore necessitated winding the center on one machine, and the outer covering on another; the described tensioning arrangement, however, permits a modification that enables the winding to be completed on one machine. 110

Thus, see Fig. 5, the tensioning mechanism may be mounted in supports 30 having spaced arms, each pulley shaft 25a being elongated to have two gears 31, 32 rotatably mounted thereon, these 5 gears having clutch members or the like 33, 34 to selectively receive a clutch collar 35 which is keyed to the pulley shaft and which is manually movable by means of a linkage 36 of standard type to obtain the desired gear engagement. 10 Since the gears 31, 32 which are operatively connected to pulley 24a and their corresponding meshing gears which are operatively connected to the other pulley, are of different diameters, the relative speeds of the two pulleys may thus be 15 selectively changed and the tension of the elastic thread made different.

If it is preferred to run the elastic thread over the pulleys in the same direction, a construction such as shown in Figs. 6 and 7 may be used, the 20 pulleys 23b and 24b having their gears 37, 38 operatively connected by an idler gear 39. This construction permits the winding of the elastic thread in the same direction in the two pulleys.

If a gradual change of tension is desired, a 25 construction such as shown in Figs. 8 and 9 may be used, in which the pulleys 23c and 24c have cone pulleys 40, 41 mounted on their respective shafts 42, 43, a slideable double bevel contact disk 44 being mounted between the cone pulleys to 30 change the tension to any desired value. The contact disk support 45 has a rack bar 47 mounted thereon, which meshes with a gear 48 that is preferably manually rotated by means of a suitable handle secured to the gear shaft.

35 It is therefore evident that the novel method and the novel construction are simple, are effective, and function regardless of the speed of movement or pull of the elastic threads. Moreover, the tension may be readily changed, as 40 by replacing one set of gears by another, or by using a clutch control, or by utilizing tapered friction rolls, the latter construction permitting gradual and progressive change in thread tension. The specific tensioning mechanism may 45 be readily applied to any machine utilizing elastic or stretchable treads, cords, or tapes.

While I have described specific structural embodiments of apparatus suitable for carrying out my invention, it is clear that desired changes in 50 size, in proportion, and in arrangement of the parts, may be made to suit the requirements or needs of different installations, within the spirit and the scope of the invention as defined in the appended claims.

55 I claim:

1. A method of winding golf balls and the like with elastic thread, comprising the steps of rotating the golf ball core to pull the thread and wind the thread thereon, maintaining a desired tension by causing the thread to move at different speeds at spaced points, and changing the relative speed during the winding.

65

70

75

2. A method of winding golf balls and the like with elastic thread, comprising the steps of rotating the golf ball core to pull the thread and wind the thread thereon, maintaining a desired tension by causing the thread to move at different speeds at spaced points, and abruptly changing the relative speed during the winding.

80 3. In a tensioning device for winding machines, spaced pulleys having thread receiving grooves, shafts for said pulleys, a plurality of gears on each shaft, and means for selectively meshing the gears on said shafts to obtain predetermined relative speeds of rotation of said pulleys.

85 4. In a tensioning device for winding machines, spaced pulleys having thread receiving grooves, shafts for said pulleys, and gearing connecting said shafts including spaced friction cones and a movable intermediate roller.

90 5. In a machine for utilizing elastic threads, means for conveying elastic thread from a source of supply to a point of use, means for maintaining the conveyed thread at a uniform tension, comprising means for regulating the speed of advance of the thread at spaced points so as to obtain different speeds of advance at said points, and means for changing the ratio of said speeds.

95 6. In a machine for utilizing elastic threads, means for conveying elastic thread from a source of supply to a point of use, means for maintaining the conveyed thread at a uniform tension, comprising means for regulating the speed of advance of the thread at spaced points so as to obtain different speeds of advance at said points, the ratio of said speeds of advance being constant, and means for changing the ratio of said speeds.

100 7. In a machine for manufacturing golf balls and the like, means for rotating a ball core to pull an elastic thread and wind the thread thereon, a tensioning device for establishing a definite tension on the thread, said thread passing therethrough, means responsive to the pull of the thread for actuating the tensioning device to apply the definite tension to the thread, and means for varying the tension which is set up in the thread by the tensioning device, during the winding of the thread.

115 8. In a machine for manufacturing golf balls and the like, means for rotating a ball core to pull an elastic thread and wind the thread thereon, a tensioning device for establishing a definite tension on the thread, said thread passing therethrough, means responsive to the pull of the thread for actuating the tensioning device to apply the definite tension to the thread, and means for abruptly varying the tension which is set up in the thread by the tensioning device, during the winding of the thread.
